(57) **CLAIM**

The ornamental design for a cleaning article, as shown and described.

DESCRIPTION

FIG. 1 is a perspective view of a first embodiment of a cleaning article showing the new design;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof;

FIG. 8 is a perspective view of a second embodiment of a cleaning article showing the new design;

FIG. 9 is a top view thereof;

FIG. 10 is a bottom view thereof;

FIG. 11 is a front view thereof;

FIG. 12 is a rear view thereof;

FIG. 13 is a left side view thereof;

FIG. 14 is a right side view thereof;

FIG. 15 is a perspective view of a third embodiment of a cleaning article showing the new design;

FIG. 16 is a top view thereof;

FIG. 17 is a bottom view thereof;

FIG. 18 is a front view thereof;

FIG. 19 is a rear view thereof;

FIG. 20 is a left side view thereof;

FIG. 21 is a right side view thereof;

FIG. 22 is a perspective view of a fourth embodiment of a cleaning article showing the new design;

FIG. 23 is a top view thereof;

FIG. 24 is a bottom view thereof;

FIG. 25 is a front view thereof;

FIG. 26 is a rear view thereof;

FIG. 27 is a left side view thereof; and,

FIG. 28 is a right side view thereof.

In the drawings, the dash-dot-dash lines represent boundaries of the claim. The portions of the cleaning article in FIGS. 1-28 shown in broken lines are included to show features that form no part of the claimed design.

1 Claim, 9 Drawing Sheets
